CLAIM

We claim the ornamental design for a cart, as shown and described.

DESCRIPTION

FIG. 1 is a front perspective view of a cart showing our new design;

FIG. 2 is a front elevation view thereof;

FIG. 3 is a left-side elevation view thereof;

FIG. 4 is a right-side elevation view thereof;

FIG. 5 is a top plan view thereof;

FIG. 6 is a bottom plan view thereof; and,

FIG. 7 is a rear elevation view thereof.

The details shown in broken lines in all views are for illustrative purposes only and form no part of the claimed design.
